UNITED STATES PATENT OFFICE.

JACOB SUMTER, OF NEW YORK, N. Y.

LETTERING-PEN.

1,263,621.

Specification of Letters Patent. Patented Apr. 23, 1918.

Application filed March 23, 1917. Serial No. 156,999.

To all whom it may concern:

Be it known that I, JACOB SUMTER, a citizen of the United States, residing at 1458 First avenue, New York city, in the county of New York and State of New York, have invented new and useful Improvements in Lettering-Pens, of which the following is a specification.

This invention comprehends the provision 10 of a draftsman's lettering pen, which is extremely simple in construction, with a view of reducing the cost of production and sale of the same to a minimum, and so designed to make letters of uniform thickness.

15 More specifically stated, the invention embodies a pair of spaced nibs parallel throughout their length, and obliquely disposed with respect to the main body portion of the pen, thus defining an ink reservoir at 20 the angular junction between the nibs and body portion, which reservoir is in open communication with the space between the nibs.

25 The nature and advantages of the invention will be better understood from the following detail description when read in connection with the accompanying drawing, the invention residing in the construction and arrangement of parts as claimed.

30 In the drawing forming part of this specification like numerals of reference indicate similar parts in the several views and wherein:—

Figure 1 is a plan view of the blank from 35 which the pen is constructed.

Fig. 2 is a side elevation.

Fig. 3 is a bottom plan view of the pen.

Fig. 4 is a transverse sectional view taken on line 4—4 of Fig. 2.

40 Fig. 5 is a similar view taken on line 5—5 of Fig. 2.

The blank from which the pen is designed, is indicated at 10 in Fig. 1 and may be any suitable material. The blank as shown embodies a relatively wide portion of uniform 45 width throughout its length, and a relatively narrow portion of uniform width throughout its length, the former merging into the latter as at 11. The relatively wide portion constitutes the main body portion 50 of the pen, and is to possess a semi-circular

outline in cross section, when the blank is curved longitudinally in the production of the pen, at which time the relatively narrow portion produces two nibs indicated at 12 55 which as shown are very narrow, but parallel throughout their entire length. The blank is split as at 13 along its longitudinal fold line for a slight distance from the free end of the narrow portion, so that the corresponding extremities of the nibs 12 will be properly separated. The nibs 12 as a unit are obliquely disposed with respect to the main body portion of the pen as clearly shown in Fig. 2, the angularity of said nibs 60 in this connection being approximately thirty degrees. With the formation of the pen in this manner coupled with the angular disposition of the nibs with respect to the main body portion, an ink reservoir 14 is 65 provided at the angular junction of the nibs 12 with the main body portion of the pen, and which reservoir is in open communication with the space between the nibs 12. This particular design of pen not only makes 70 letters of uniform thickness as illustrated in Fig. 6, but will not overflow, and yet holds a considerable supply of ink. The pen in addition to being cheap to manufacture, can be readily and easily cleaned when desired by moving the sharp edge of a piece 75 of paper through the space between the nibs 12. The pens can be made of any size, and if properly proportioned can be used in conjunction with the ordinary and well known 80 form of pen holder.

It is believed that from the foregoing description the nature and advantages of the invention will be apparent, and while I have shown and described what I consider the 90 preferred embodiment of the invention, I desire to have it understood that such changes in the construction and arrangement of parts may be resorted to when desired as fall within the scope of what is 95 claimed.

What is claimed is:—

A pen comprising a body having its sides curved downwardly and a gradually constricted neck portion having parallel sides 100 merging into the sides of said body portion, said neck portion inclining downwardly in

respect to the top of said body portion and being longitudinally bifurcated to provide normally spaced parallel nibs, the ends of said nibs being at right angles to the neck portion the thickness of said nibs in a vertical direction being greater than their thickness in a lateral direction, whereby sep-

aration of said nibs upon downward pressure thereon will be prevented, the juncture of said neck portion with said body serving as an ink reservoir.

In testimony whereof I affix my signature.

JACOB SUMTER.
